US00D945931S

(12) **United States Design Patent** (10) Patent No.: **US D945,931 S**
(45) Date of Patent: **** Mar. 15, 2022**

(54) **TRUCK**

- (71) Applicants: **Hyundai Motor Company**, Seoul (KR); **Kia Motors Corporation**, Seoul (KR)
- (72) Inventors: **Jae Kyu Kim**, Gyeonggi-do (KR); **Seong Jae Shin**, Gyeonggi-do (KR); **Jun Gu Lee**, Incheon (KR)
- (73) Assignees: **Hyundai Motor Company**, Seoul (KR); **Kia Motors Corporation**, Seoul (KR)

(**) Term: **15 Years**

(21) Appl. No.: **35/510,734**

(22) Filed: **May 8, 2020**

(80) **Hague Agreement Data**

Int. Filing Date: **May 8, 2020**

Int. Reg. No.: **DM/208368**

Int. Reg. Date: **May 8, 2020**

Int. Reg. Pub. Date: **Nov. 13, 2020**

(30) **Foreign Application Priority Data**

Dec. 5, 2019 (KR) 30-2019-0058886

(51) **LOC (13) Cl.** **12-08**

(52) **U.S. Cl.**

USPC **D12/93**
